HOLLOW DRUM GRATER WITH FEED SCREW REINFORCING MEMBER

Joseph E. Rustici, Stamford, Conn.

Application June 22, 1946, Serial No. 678,620

4 Claims. (Cl. 146—92)

1

This invention relates to a food grater, and more particularly to a grater adapted to grate a relatively hard substance such as hardened cheese.

I have conceived and reduced to practice an improved grater in which the grating element is cylindrical and formed of very thin sheet metal. This thin sheet metal when punched, yields a barbed grating surface that is extremely effective for the general purpose indicated. Moreover, it remains effective for long periods of time. However, a thin barbed surface as described, is relatively fragile so that when hard cheese is pressed thereagainst, it will bend and otherwise yield and become deformed.

As part of my invention I have conceived and applied a novel reinforcing means to a thin sheet metal grater of the type described, the reinforcing means acting effectively to maintain the sheet metal surface in its proper form while in no way hindering its operation and function.

As a feature of this part of my invention, I utilize a thin rib-like reinforcing member within the cylindrical form of the thin sheet metal grater, and preferably the reinforcing member may take the form of a feed screw.

As a further feature of the invention, I arrange the casing of my grater so that the cheese to be grated will lie in contact with a considerable portion of the grater extending upwardly from its lowermost position. In this way, the cheese is more effectively grated and considerably less thereof will move against the end surface defining the mouth between the chamber in which the cheese lies, and the chamber in which the grater rotates.

I have thus outlined rather broadly the more important features of my invention in order that the detailed description thereof that follows may be better understood, and in order that my contribution to the art may be better appreciated. There are, of course, additional features of my invention that will be described hereinafter and which will form the subject of the claims appended hereto. Those skilled in the art will appreciate that the conception on which my disclosure is based may readily be utilized as a basis for the designing of other structures for carrying out the several purposes of my invention. It is important, therefore, that the claims to be granted me shall be of sufficient breadth to prevent the appropriation of my invention by those skilled in the art.

Referring now to the drawings, Fig. 1 is a perspective view of the grater of my invention. Fig. 2 is a vertical section taken along lines 2—2 of Fig. 1. Fig. 3 is a vertical section taken along lines 3—3 of Fig. 2. Fig. 4 is an exploded view of a part of the thin sheet metal grater and the reinforcing member utilized therewith.

2

Referring now more particularly to the drawings, my cheese grater comprises a casing 10 supported by a bracket 11 whereby it may be secured through the screw fastening member 12 to a table, stand, or the like. As a matter of fact, the casing may be secured in many ways so as to be held stationary during the grating operation.

The casing 10 comprises a lower chamber 13 and an upper chamber 14. The side plates 15 of the upper chamber are connected at their upper ends by a plate 16 utilized to guide a rod 17 having secured at its upper end a knob 18 whereby downward pressure may be applied to the rod 17. A pressure plate 19 is secured to the lower end 15 of the rod 17 and it is through means of this pressure plate 19 that cheese is pressed downwardly against the grater to be presently described. One end wall of the upper chamber 14 is open as indicated at 20 for the insertion of the cheese, the other end of the chamber 14 being closed by an end wall 21.

The grater of my invention is in the form of a thin cylindrical sheet metal member 22 having a surface that is pierced to form a series of barbs 23 that are extremely effective for grating cheese or the like. For supporting and rotating the grater 22 in the chamber 13, I preferably utilize a shaft 24 having formed integrally with one end thereof a plate 25 onto which one end of the cylindrical grater 22 is fitted as best seen in Fig. 3. Also, as best seen in Fig. 3, the shaft 24 is formed with a bearing portion 26 whereby it is supported at its right hand end in a bearing 27 of the casing 10. A turning handle 28 may be fitted onto the end 29 of the shaft 24 and held thereon by a screw fastener 30 in a conventional manner.

The left hand end of the shaft 24 is formed with a bearing portion 31 adapted to be supported in a bearing 32 carried by an end plate 33 that is secured to the casing 10 by wing nuts 34 fitted on studs 34a as best seen in Fig. 1. Formed also on the left hand end of the shaft 24 is a ring 35 equipped with a lug 36. It is the function of this lug to co-act with a struck in lug 37 formed as an integral part of a spider plate 38. This spider plate 38 is secured to the left end of the thin cylindrical sheet metal grater 22 as best seen at 39 in Fig. 4. It is now obvious that rotation of the shaft 24 by the handle 28 will act to rotate the said shaft and that this rotation will rotate the cylindrical grater 22 through the medium of lugs 36 and 37.

Those skilled in the art will fully appreciate that the considerable force required to press hard cheese through pressure plate 19 against grater 22 to grate the cheese, will act to bend and otherwise deform the said grater. To arrange for a thicker sheet material is quite simple, but barbs formed in thicker sheet metal will not function as

well as the thinner sheet metal utilized by me, and in addition, thick sheet metal is more difficult to fabricate into a barbed cylinder. To reinforce the relatively thin sheet metal of the grater 22, the shaft 24 has secured thereto a screw-like rib member 40, the periphery 41 of which lies against the inner surface of the grater and reinforces the grater in a manner that will be quite apparent to those skilled in the art. It should be emphasized that while I prefer to utilize a screw form of reinforcing member, it is really possible to use any other type of rib-like structure that will reinforce the sheet metal but will not obstruct or hinder its operation and the efficiency of the barbs thereof.

The chamber 13 has a sloping lower wall 42 terminating in a discharge mouth 43. In vertical alignment with this discharge mouth there are a series of relatively large openings 44 in the grater 22. It will be well at this point to indicate further that the grater 22 is positioned, as best seen in Fig. 2, across the mouth between chamber 14 and chamber 13 so that no cheese can be sent into the chamber 13 except through the medium of the bark holes of the grater, or by passage through the space between the grater 22 and the lower edge 21a of the wall 21. It will be well to note further at this point that any cheese in the chamber 14 will be in contact with the grater 22 during a considerable movement of the grater surface upwardly rather than downwardly. This is possible because of the offset relationship between chamber 14 and chamber 13.

In operation, the cheese is inserted into the chamber 14 through the opening 20 and pressure is applied thereagainst by pressure plate 19, forcing the cheese against the surface of the grater 22. The barbs 23 grate the cheese and it will drop down into the interior of the grater where it will tend to lie on the bottom inside surface thereof rather than rotate with the grater. The cheese will, therefore, be fed by the screw feed member 40 toward and into openings 44 of grater 22 and downwardly through the mouth 43 of the chamber 13. Some of the cheese will, of course, adhere to the surface of the grater between the barbs thereof and will move past the lower edge 21a of the end wall 21 and thus be dropped onto the sloping surface 42 of the chamber 13. This cheese will gradually move by gravity to the mouth 43.

I believe the construction and the functioning of my invention will now be apparent to those skilled in the art.

I now claim:

1. In a device of the class described, a casing, a thin cylindrical sheet metal grater having a series of punched grater portions on its outer periphery, means whereby said cylindrical grater rotates in a predetermined axis relatively to said casing, a feed screw having a diameter equal to the internal diameter of said cylindrical grater supported within said cylindrical grater and having a continuous outer rib-like surface applied against the inner surface of said grater for reinforcing the grater against pressure applied thereto while the continuous surface of said screw feeds the grated product toward one end of said cylindrical grater, means whereby said feed screw and cylindrical grater are rotated together in said predetermined axis, said feed screw terminating within said cylindrical grater in spaced relation to said one end thereof, and said one end having a relatively large opening to receive the grated product as fed by said feed screw for movement outwardly of said cylindrical grater.

2. In a device of the class described, a casing, a thin cylindrical sheet metal grater having a series of punched grater portions on its outer periphery mounted for rotation in a predetermined axis within said casing, a feed screw having a portion coaxial with said cylindrical grater and supported within said cylindrical grater, said feed screw having also a continuous outer rib-like surface extending from said coaxial portion continuously against the inner surface of said grater for reinforcing the grater against pressure applied thereto, means whereby said feed screw and cylindrical grater are rotated together, said feed screw terminating within said cylindrical grater in spaced relation to said one end thereof, and said one end having a relatively large opening to receive the grated product as fed by said feed screw for movement outwardly of said cylindrical grater.

3. In a device of the class described, a casing, a thin cylindrical sheet metal grater having a series of punched grater portions on its outer periphery mounted for rotation in a predetermined axis within said casing, a feed screw supported within said cylindrical grater with an axial portion thereof coaxial with said grater and having an outer rib-like surface extending from the said axial portion thereof continuously toward and against the inner surface of said grater for reinforcing the grater against pressure applied thereto, means for rotating said grater and feed screw together in said predetermined axis, said cylindrical grater having a series of relatively large openings located in a position to receive the grated product as propelled by said feed screw whereby said product will drop outwardly from within the grater.

4. In a device of the class described, an upper chamber for housing a piece of material to be grated, a lower chamber in communication with said upper chamber through a mouth, and laterally offset relatively to said upper chamber, a thin cylindrical sheet metal grater having a series of punched grater portions on its outer periphery, means mounting said grater in the lower chamber with a portion of its periphery always positioned across said mouth, said mouth exposing to said upper chamber an upwardly extending part of said grater periphery substantially larger than the downwardly extending portion thereof so exposed so that the material to be grated may be forced against the cylindrical grater surface with a substantial portion of the material on said upwardly extending part of the grater periphery, and a feed screw within said grater having a continuous outer rib-like surface against the inner surface of said grater for reinforcing the grater against pressure applied thereto by the material in said upper chamber to be grated.
